UNITED STATES PATENT OFFICE.

HENRY HARTIG, OF BROOKLYN, NEW YORK.

STEAM-ENGINE.

SPECIFICATION forming part of Letters Patent No. 277,897, dated May 22, 1883.

Application filed October 7, 1882. (No model.)

To all whom it may concern:

Be it known that I, HENRY HARTIG, of Brooklyn, in the county of Kings and State of New York, have invented certain new and useful Improvements in Steam-Engines, of which 5 the following is a specification.

This invention has reference to improvements in reciprocating steam-engines in which an oscillating slide-valve is arranged at the interior of the hollow piston; and it consists of a cylinder closed at one end and provided at the other end with a circular casing, and of a reciprocating hollow piston having interior valve-seats for an oscillating cylindrical slide-valve. The slide-valve is recessed with steam-passages at opposite sides, which communicate with the steam supply and exhaust ports of the cylinder. A connecting crank-rod of 10 the driving-shaft passes through a recess of 20 the cylindrical slide-valve, and is jointed thereto by a ball-and-socket joint and pivoted at 25 its outer end to the piston.

In the accompanying drawings, Figures 1 and 2 are vertical longitudinal sections of my 25 improved steam-engine, showing the piston in two different positions. Fig. 3 is a vertical transverse section of the same, taken on a plan at right angles to the sections shown in Figs. 1 and 2; and Figs. 4 and 5 are respectively a detail top view of the piston and a detail section of the slide-valve.

Similar letters of reference indicate corresponding parts.

Referring to the drawings, A represents the 35 cylinder of my improved steam-engine, which is closed at one end by a head, A', and provided at the other end with a circular casing, A''. The cylinder A is arranged either in vertical or horizontal position, as desired. The 40 circular portion A'' is provided at one or both sides with suitable bearings and stuffing-boxes for the driving-shaft B, that carries at its inside the crank B', to which latter the connecting-rod C is pivoted in the usual manner.

The piston D is open at both ends and fitted 45 tightly to the interior bore of the cylinder A. It is provided with a central opening extending through its entire length and nearly midway of its length, with inwardly-projecting 50 concave cheeks or seats d for the oscillating slide-valve E. The piston D is arranged at opposite sides with recesses d' d'', that commun-

icate, respectively, with the steam supply and exhaust ports b and b', which ports are arranged at opposite sides of the cylinder A. 55 The piston D supports the oscillating slide-valve E by the cheeks d, said slide-valve extending transversely from one recess, d', to the other, as shown in Fig. 3. The oscillating slide-valve E is provided at diametrically-opposite sides with longitudinal steam-passages e e, one of which extends from the recess d' at one side of the piston D to a shoulder, e', at the opposite end of the slide-valve, while the recess e at the opposite side of the slide-valve 65 extends from the recess d' at the opposite side of the piston D to a shoulder, e', of corresponding size at that end of the slide-valve E near the steam-supply port.

The connecting-rod C is seated by a ball-and-socket joint, f, in the lower part of the slide-valve E, extended through the centrally-recessed portion of the same, and pivoted at its outer end to the piston D, as shown clearly in 70 the drawings.

By admitting steam through the supply-port b, it passes through recess d' of the piston and steam-passage e of the slide-valve E to the interior of the cylinder, filling the space at one side of the piston, while the steam is simultaneously exhausted through the opposite steam-passage e, recess d', and exhaust-port b'. The piston D is thereby moved forward, and the crank of driving-shaft carried thereby, by the connecting-rod C, through one-half of 85 its revolution. A balance-wheel on the driving-shaft (not shown in the drawings) assists the crank of the driving-shaft to pass over the dead-points in the usual manner, and causes thereby the reversal of the oscillating piston, 90 so that live steam enters into that part of the cylinder that has just exhausted, while the steam is exhausted from that part that has before received live steam. The revolution of the driving-shaft is thereby completed. The 95 reciprocating motion imparted to the piston produces the regular rotary motion of the shaft.

The arrangement of the oscillating slide-valve at the interior of the piston furnishes a steam-engine of simple and compact construction, which is specially adapted for machines 100 of smaller size and power.

Having thus described my invention, I claim as new and desire to secure by Letters Patent—

1. The combination, with a steam-cylinder closed at one end and provided with a circular casing at the opposite end, of a hollow reciprocating piston, of a connecting-rod pivoted to the driving crank-shaft and the piston, and of an oscillating slide-valve arranged at the interior of the piston and being jointed to the slide-valve, substantially as set forth.

2. In a steam-engine, the combination of the cylinder closed at one end and provided with a circular casing at the opposite end, a hollow reciprocating piston having recesses at opposite sides and interior seats, an oscillating slide-

valve having a central recess and steam-passages at both sides, and a connecting-rod that is pivoted to the crank of the driving-shaft, applied by a ball-and-socket joint to the oscillating slide-valve, and pivoted at its outer end to the piston, substantially as specified.

In testimony that I claim the foregoing as my invention I have signed my name in presence of two subscribing witnesses.

HENRY HARTIG.
